[57] **CLAIM**

The ornamental design for an element of a shoe sole, as shown and described.

DESCRIPTION

FIG. 1 is a side elevational view of an element of a shoe sole showing my new design;

FIG. 2 is a side elevational view of the other side thereof;

FIG. 3 is a front elevational view thereof;

FIG. 4 is a rear elevational view thereof; and,

FIG. 5 is a cross section taken along the line 5—5 of FIG. 2.

The broken line showing of a shoe upper and the remaining portion of the shoe sole shown in FIGS. 1—5 is for illustrative purposes only and forms no part of the claimed design.
